UNITED STATES PATENT OFFICE.

JOHN H. PEGG, OF WABASH, INDIANA.

VAULT.

1,324,518.

Specification of Letters Patent.

Patented Dec. 9, 1919.

Application filed December 28, 1918. Serial No. 268,768.

To all whom it may concern:

Be it known that I, JOHN H. PEGG, a citizen of the United States, residing at Wabash, in the county of Wabash and State 5 of Indiana, have invented a new and useful Vault, of which the following is a specification.

The object of my invention is to provide an improved reinforced concrete vault having an improved double reinforced concrete 10 base so arranged as to prevent water from entering the vault, and to render same air tight.

In the accompanying drawings, illustrating my invention—

Figure 1 is a side elevation of the exterior of the vault;

Fig. 2 is a vertical longitudinal section of my vault;

Fig. 3 is a horizontal section on line 3—3 of Fig. 2; and

Fig. 4 is a transverse section on line 4—4 of Fig. 2.

Like numerals designate like parts in the several views.

Referring to the accompanying drawings, I provide a suitable reinforced concrete base 2 having an encircling downwardly extending wall 1 spaced from the outer 30 edge 11 of base 2 and terminating in an encircling outwardly-extending extension base 4 having its outer edge 12 positioned in a plane substantially beyond the edge 11 of member 2 and adapted to support the bottom 35 edge 5 of the upright wall 6 of the vault body. I further provide a suitable encircling cutaway portion 3 of upright wall 6 to permit of wall 6 resting on base 2, as shown in Fig. 4. Base 2 is provided with 40 suitable casket-supporting rests 9. Concrete wall 6 is provided with suitable metal reinforcing ribs 8, and base 2 and extension walls 1 and 4 are provided with similar 45 suitable reinforcing ribs 8. I further provide a suitable wire netting reinforcement 7 in the various concrete walls, as illustrated in the drawings. By the construction illustrated, an encircling air chamber 10 is provided about the base of the vault, 50 formed by members 2, 3, 1 and 4, as shown in Figs. 2 and 3. A further air chamber 13 is formed under the concrete base 2 to protect same from water. A water-proof vault is thus provided, having an air cham-

ber encircling the joints of the base of the 55 vault and an air chamber under the base of the vault, with a construction that is comparatively simple and which may be built at relatively small expense.

I further provide suitable bars or grip 60 members 14 at either end of the outer walls of the vault spaced a suitable distance from the upper edge of the vault and providing a means for fastening a rope about the vault for moving same. 65

What I claim is:

1. A plastic reinforced vault comprising a reinforced base, a reinforced vault body mounted on the base, the body member having an offset portion, the base of the 70 vault having a downwardly extending wall, a horizontally extending wall extended from the latter wall, said walls coöperating with the offset part of the vault body and its base to form an encircling air space, whereby to insure a damp-proof and air-proof vault. 75

2. A plastic reinforced vault comprising a metal and wire reinforced body having an encircling cut away portion near the bottom 80 of its upstanding walls, a similarly reinforced base projecting to engage said cut-away portion, the base of the vault having a downwardly extending wall, a horizontally extending wall extended from the latter 85 wall, said walls coöperating with the offset part of the vault body and its base to form an encircling air space, whereby to insure a damp-proof and air-proof vault.

3. A plastic vault having metal rods and 90 wire netting reinforcing same and comprising a vault body having an encircling cut-away portion near the bottom of its up-standing walls, a base on which the body of the vault rests at the cut-away portion, a 95 substantially L-shaped base extension extending outwardly beneath and encircling the base of the vault and having the outer edge of said extension supporting the vault body, said extension also forming an encircling air chamber extending around the bottom outer portion of the vault beneath the base, substantially as shown. 100

JOHN H. PEGG.
